UNITED STATES PATENT OFFICE.

JOHN H. BECKER, OF BROOKLYN, NEW YORK, ASSIGNOR TO WARP TWISTING-IN MACHINE COMPANY, OF BROOKLYN, NEW YORK, A CORPORATION OF NEW YORK.

WARP-TWISTING-IN MACHINE.

1,403,067.

Specification of Letters Patent. Patented Jan. 10, 1922.

Application filed November 24, 1920. Serial No. 426,123.

To all whom it may concern:

Be it known that I, JOHN H. BECKER, a citizen of the United States, residing at Brooklyn, in the county of Kings and State 5 of New York, have invented certain new and useful Improvements in Warp-Twisting-In Machines, of which the following is a specification.

This invention relates to warp twisting-10 in machines of the class set forth in U. S. Letters Patent Nos. 648,738, 675,350, 686,724, 695,566 and 810,711. In these machines the end portions of the two warps (old and new) whose threads or "ends" are to be 15 twisted together are arranged to project upwardly side by side, each having a cross therein, and their crosses are maintained by horizontally projecting and horizontally reciprocating hook-bars which draw back 20 edgewise first one and then the other of the crossed sheets of threads composing each warp and in this way release one by one the outermost threads, turning half-revolutions between their drawing-back movements. 25 The means to hold the upward extremity of each warp must so hold it that its outermost margin (the one from which the threads are one by one separated and then advanced by feeding means to the twisting 30 mechanism) is not forward of the hooks on the hook-bars at the moment they turn, else the hooks in turning will enter into the mass of threads instead of forward or clear of the same. On the other hand, it is very desir- 35 able in these machines that when the main body of the warp is drawn back to leave the outermost thread separated the gap formed should be as considerable as possible, thus to break down filament connections which 40 might prevent the separation, at least to such an extent that the feeding means would fail to pick off the thread supposed to be released. Accordingly, by the present invention I have made provision for move- 45 ment of the said holding means lengthwise of the hook-bars and back and forth, such movement being timed so that the warps will be held back when the hook-bars are turning, thus to allow them to turn without 50 entering the mass of threads, and held forward when the hook-bars draw back the main body of each warp, thus to increase the gap between each released thread and the main body of threads. In that adapta-

tion of my invention herein particularly 55 shown and described the movements of said holding means result from movement of a structure (carrying it) which moves the up- 60 standing portion of each warp up and down, as in the patents referred to, relatively to 65 the hook-bars to break down the filamentous connections between the threads; but it will be understood that my invention is not de- 70 pending on such up and down movement and that the movements of the holding means 75 may be accomplished otherwise than as stated.

In the drawings,

Figure 1 shows in side elevation, partly broken away, a warp twisting-in machine 70 embodying my invention, the aforesaid up- 75 and-down movable structure and the holding means being respectively shown in their upward and forward positions;

Figure 2 is a vertical transverse sectional 80 view looking rearward and taken just for- 85 ward of the hook-bars;

Figure 3 shows in side elevation the upper 90 part of the machine, said structure and hold- 95 ing means being respectively in their de- 100 pressed and rearward positions;

Figure 3^a is a rear fragmentary view, 105 showing a certain cam;

Figures 4 and 5 are detail views in side 110 and end elevation, partly in section, of a 115 part of the holding means and the portion of said structure in which it moves; and

Figures 6 and 7 are a plan and a side 120 elevation of said part.

The base *a* and upright *b* of the frame of 125 the machine; the suitably rotated main shaft *c* and cam *d*, roller-carrying wheel *e* and pin *f* thereon; the spaced stationary rods *h* pro- 130 jecting forward from the upright *b* and over 135 which the two warps respectively extend, 140 and, between said rods, the fork *i* under 145 and then upwardly between the arms of 150 which the two warps next extend, the same 155 being moved back and forth by having an 160 arm *i'* engaged in cam *d*; the warp drawing- 165 back means *j* in the form of rotary and for- 170 wardly and backwardly movable hook-bars 175 projecting from said upright and arranged 180 in two pairs extending between the crossed 185 sheets of the respective warps (Figure 2) 190 with one hook-bar in each pair above and 195 the other below the cross; the means to trans- 200 mit half-revolutions to said hook-bars in-

cluding the star-wheel k engageable by the pin f on wheel e , a gear l rotating with said star-wheel, pinions m appertaining to the respective hook-bars and one of which meshes with gear l , and a gear n meshing with all of said pinions; the slide o moved back and forth, from cam d , on a projection b' of the upright and having the rear end portions of the hook-bars swivelled therein; 10 the up-and-down movable structure p carrying on its forwardly projecting arm p' the aforesaid holding means (to be described in detail) and also carrying at its lower (forked) end the forwardly projecting rods 15 q , so that when said structure is moved up and down by engagement of roller e' on wheel e with its cross-slot r the crossed warps will be moved, without slackening, relatively to the hook-bars to break down filamentous 20 connections joining the threads thereof; the twisting means generally denoted by s ; the means to advance to means s the warp threads as fast as they are separated, consisting in the example shown of a suitably 25 rotated spiral t ; and the swinging finger t' which is suitably moved in a vertical plane from its position in Figure 1 to its position in Figure 3 and is adapted in the latter position to hold back the main body of each 30 warp, are or may be all substantially the same as in the patents hereinbefore mentioned. The gearing connections are such that, as in the patents, the hook-bars perform the half-revolutions when forward; 35 and they are forward, it may be also noted, when the structure p is depressed and back when said structure is elevated (compare Figures 1 and 3.)

u designates a pair of carriages each having 40 a pivoted clip u' for clamping the warp, each carriage being normally held forward by springs v all the same as in Patent No. 810,711. In that patent the carriages acted under pressure of the springs to press the 45 warps edgewise against a horizontal bar (123) so that as fast as the warps on being twisted together had their upstanding ends cut away said carriage would feed forward the unsevered upstanding ends; the position 50 of this bar in the patent is in a vertical plane back of the hooks on the hook-bars when they are in the position for turning or fully forward. Such a bar or equivalent stop w is included according to my present invention, but it is movable, forming part of a 55 slide x which moves in suitable ways y (Figures 4 and 5) at the under side of projection p' and is forked at its rear end to accommodate structure p and a cam z fixed to upright b and has a roller 2 to bear on said cam.

The cam z is so formed that when the structure p is depressed stop w will stand in its rearmost position (Figure 3), thus pressing back the warps and consequently, 60 through them, the forwardly spring-pressed

warp clamping carriages u , since the hook-bars are to revolve at this time; and that when said structure is elevated (Figure 1) the springs v are free, by forward pressure on the carriages, to cause the warps to be held by the clamps considerably forward of their former positions, so that an ample gap A results between the thread released by the action of the hook-bars and the main body of thread in each warp. 75

Of course my invention is not limited to the specific combinations of parts shown, the underlying principle being the movement of warp holding means back and forth longitudinally of the hook-bars, said means being held back when the hook-bars are forward and turned and held forward when the hook-bars are back; and so, broadly, it is not material that there is up and down movement, or that the movement of the holding means back and forth is an incident of this movement, or that the holding means takes the form of a wrap carriage and a stop (as w) against the latter of which the former, spring-pressed, presses the warp so as to bring the uncut threads always forward to a definite position. 80

By my invention there is not only produced the desired gap A , but a certain amount of movement of the warp crosswise 95 which is very helpful in breaking down filament connections between the threads, especially since there is some shifting of the carriages relatively to the stop w always going on. 100

Having thus fully described my invention, what I claim as new and desire to secure by Letters Patent is:—

1. Mechanism for effecting release one after another of the cross threads of two sheets 105 of warp including, with a revoluble hook-bar adapted to be interposed between the warp sheets and movable crosswise and against an edge of the warp to draw back the crossed threads, holding means for the warp also movable crosswise thereof, a driving means, and means to transmit to the hook-bar from the driving means half-revolution movements and between such movements and to the hook-bar and warp holding-means reciprocations in opposite directions and crosswise of the warp. 110

2. Mechanism for effecting release one after another of the crossed threads of two sheets of warp including, with a revoluble 120 hook-bar adapted to stand interposed between the warp sheets and to engage an edge of the warp to draw back the crossed threads, holding means for the warp movable crosswise thereof, a driving means, and means to transmit to the hook-bar from the driving means half-revolution movements and between such movements and to the warp-holding means a movement crosswise 125 of the warp in the direction to allow the 130

warp to engage and be held back at said edge by the hook-bar, and then a movement in the opposite direction.

3. In combination, with a fixed structure, 5 a hook-bar arranged to rotate therein, a supporting structure movable in the fixed structure, warp holding means movable in the supporting structure substantially parallel with the hook-bar, said hook-bar being 10 adapted to stand interposed between the sheets of crossed warp threads, and means to turn the hook-bar at intervals a half-revolution and on each turning move the supporting structure, said fixed structure having means to move the work holding means 15 in the supporting structure on movement of the latter.

4. In combination, with a fixed structure, 20 a hook-bar arranged to rotate therein, a supporting structure movable in the fixed structure, warp holding means movable in the supporting structure substantially parallel

with the hook-bar, said hook-bar being adapted to stand interposed between the sheets of crossed warp threads, and means to 25 turn the hook-bar at intervals a half-revolution and on each turning reciprocate the supporting structure, said structures having co-acting means to move the warp holding means back and forth in the supporting 30 structure on each reciprocation of the latter.

5. In combination, with the frame and movable structure of a machine of the kind specified, a warp-clamping carriage movable back and forth in said structure and 35 spring-held in one direction, a cam on the frame, and a warp-stop movable back and forth with said carriage and bearing against the cam and opposing movement of the carriage in said direction, all substantially as 40 set forth.

In testimony whereof I affix my signature.

JOHN H. BECKER.
